Nelson Howard

UNITED STATES PATENT OFFICE

ANDREW EPPLER, OF LYNN, MASSACHUSETTS, ASSIGNEE TO UNITED SHOE MACHINERY CORPORATION, OF PATERSON, NEW JERSEY, A CORPORATION OF NEW JERSEY

PRESSING MACHINE FOR USE IN THE MANUFACTURE OF BOOTS AND SHOES

Application filed December 30, 1927, Serial No. 243,703. Renewed March 25, 1931.

This invention relates to pressing machines for use in the manufacture of boots and shoes and is illustrated as embodied in a machine for pressing the joint or lap of the 5 welt of shoes to reduce the thickness of the welt at the joint in order that the shoe edge may be of substantially uniform thickness, thereby improving the appearance of the shoe.

- 10 In the manufacture of stitchdown shoes, particularly those of the smaller sizes, it is usual to turn outwardly the margin of the upper materials all the way round the shoe and to apply a false welt, so called, upon 15 the outturned flange of the upper, the welt, of course extending entirely around the shoe and being attached by a seam securing the outturned flange of the upper to a sole. This sewing operation is always begun on the 20 inner side of the shoe and continued completely around the periphery of the shoe. When, at the completion of the sewing operation, the end of the welt first attached is reached, it is necessary to form a joint at 25 the ends of the welt. Various common types of joint for uniting the ends of pieces without producing extra thickness at the joint may be employed, but these require more time and skill on the part of the operator than is justified by this class of work. 30 Accordingly, it is a common practice, after the welt has been sewed on completely around the shoe, to overlap the welt on the welt end already attached and to continue 35 the seam for a few stitches through both thicknesses of the welt, the upper and the sole. The operator then stops the machine, draws the shoe away from the machine with the welt attached, and cuts off the welt 40 through the last stitch made. In cutting off the welt the operator will sever it at an angle so that the second end of the welt is beveled, the first end having been similarly beveled before attachment of the welt to the shoe. 45 Of course, where the ends of the welt overlap, there is a thicker appearance of the shoe edge which is objectionable. The term "welt lap" as hereinafter used is meant to include any form of welt lap such that the 50 joint is thicker than the remaining portion

of the welt unless the term is shown by the context to refer to the form of joint above described.

Objects of the invention are to provide an improved machine for pressing welt laps to 55 reduce the thickness of the shoe edge at the welt lap to the thickness of the remainder of the shoe edge, and to provide a machine for this work which can be operated rapidly and with a minimum of effort on the part of the 60 operator.

In view of the foregoing, the invention provides a welt lap pressing machine comprising a tool for engaging the upper surface of the 65 welt at the welt joint, a support for engaging the bottom of the shoe opposite to the welt joint, and power-operated means for effecting relative movement between the tool and support to compress the material at and adjacent to the welt joint, thus reducing the 70 shoe edge to normal thickness. Preferably and as illustrated, the tool is arranged in a fixed position at a downward and outward inclination with respect to the machine so that the shoe can be presented to the tool 75 with the portion of the shoe at which the welt joint occurs in full view of the operator, and the support is moved relatively to the tool in a direction perpendicular to the welt engaging surface of the tool by power means 80 operating through a lever having a yielding fulcrum whereby powerful pressure may be applied to the shoe materials between the tool and support. As illustrated, the fulcrum is 85 maintained in position by a spring the initial tension of which is adjustable, the spring being brought into action after a predetermined pressure has been applied to the welt to prevent excessive pressure on the welt or undue strain or breakage of the machine. Preferably the power-operated means is controlled by a clutch of the repeating type which will permit, when desired, rapidly repeated impulses to be imparted to the shoe support to effect 90 progressively the desired flattening of the welt joint.

These and other features of the invention will appear more fully from the following description when read in connection with the

accompanying drawings and will be pointed out in the appended claims.

In the drawings,

Fig. 1 is a side view of a welt lap pressing machine embodying the present invention;

5 Fig. 2 is a sectional view of a part of the machine showing its operation upon a shoe;

Fig. 3 is a perspective view of part of a shoe before being operated upon by the machine; and

10 Fig. 4 is a similar view of the shoe after being operated upon.

The illustrated machine is designed for pressing the welt lap of a stitchdown shoe in which the welt is carried around the shoe and the ends lapped one upon the other. In Fig. 1 of the drawings, the numeral 10 indicates a column on the top of which a head 12 is secured. In the upper part of the head 12 is 15 a bearing 14 having a hole the axis of which is inclined at about thirty degrees from the vertical and in which is mounted a sleeve 16 the lower part of which is formed as a welt pressing tool 18. The outer end of the tool 18 is beveled off on its upper side so that it can enter the angle between the side of the shoe and the welt and its outer end is slightly rounded to fit the curvature of the shank where the welt joint occurs. The working 20 face 20 of the tool 18 is flat and has sufficient lateral extent to cover the welt lap. On the face 20 of the tool an abutment 22 is provided, the abutment being mounted on the tool by means of screws 24 threaded into the tool 18 and passing through a slot in the abutment so that the abutment can be adjusted 25 toward and from the outer end of the tool. The sleeve 16 is secured in the bearing 14 by means of a nut 26 threaded on the sleeve, tightening of which clamps an enlargement 28 of the sleeve and a washer 30 against the lower end of the bearing 14. In the sleeve 16 may be placed an electric heating unit 32 the terminals of which are indicated at 34.

30 To cooperate with the welt pressing tool 18 a support 36 for the sole of the shoe is provided. The sole engaging face of the support has an extent both laterally and outwardly somewhat greater than that of the welt pressing face 20 of the tool, and its lateral and outer margins are rounded off to eliminate any sharp corners that might mar the shoe bottom during the pressing operation. A portion of the upper face of 35 the support is recessed to avoid contact with the screws 24 which secure the abutment 22 in position. The support 36 has a stem 38 threaded into a slide 40 mounted for movement at right angles to the welt engaging face 20 of the tool 18. The stem 38 carries a set nut 42 to hold the support 36 in fixed relation to the slide after it has been adjusted relatively to the tool 18 by turning the stem in the slide.

40 The lower end of the slide 40 is connected

by a link 44 to a lever 46 which is fulcrumed at 48 on a yielding plunger to be described.

At an intermediate point 50 the lever 46 is connected to an eccentric rod 52 on which is an eccentric strap 54 engaging an eccentric 70 56 on a shaft 58, the eccentric giving a constant stroke to the intermediate point 50 of the lever 46.

In order that excessive pressure may not be applied to the work and that undue strain 75 on the machine parts and breakage thereof may be avoided, the fulcrum 48 of the lever 46 is arranged to yield. To this end the fulcrum pin 48 passes through a plunger 60 which is mounted for movement in a lug 62 on the frame in a direction parallel to the slide 40. Pinned to the plunger 60 is a head 64 which normally rests upon the lug 62 against which it is held by a spring 66. The opposite end of the spring 66 abuts against 80 a member 68 mounted for movement lengthwise of the spring in a lug 70 on the frame. In the upper portion of the lug 70 is threaded a screw 72 which bears against the member 68 and by turning which initial tension 85 of the spring 66 may be adjusted, the adjustment being maintained by a set nut 73. The spring 66 is sufficiently stiff so that heavy 90 pressure is applied to the work by operation of the eccentric 56. In case the thickness 95 or resistance to compression of the work is sufficient, the spring 66 will yield to prevent breakage of the machine and to cause no more than a predetermined pressure to be applied to the work. The eccentric 56 is 100 fixed to the shaft 58, and a pulley 74 is loosely mounted on the shaft 58. Between the pulley 74 and the eccentric shaft 58 any suitable form of clutch mechanism may be provided. The clutch illustrated is substantially similar 105 to that disclosed in United States Letters Patent No. 1,351,138, granted August 31, 1920, on application of R. B. Smith. The clutch is controlled by a vertical slide rod 76 normally upheld by a spring 78. The 110 upper end of the rod is arranged to engage a wedge-shaped member 80 arranged to slide axially of the shaft and to rotate with the shaft when the shaft turns. The member 80 carries a projection 82 which, when allowed 115 to move axially of the shaft with the wedge member, engages a cooperating projection or opening in the pulley 74 to effect rotation of the eccentric. The rod 76 is depressed by a lever 86 fulcrumed at 88 to the frame and 120 having attached to its forward end at 90 a treadle rod 92 which, at its lower end, is connected to a clutch operating treadle (not shown). Depression of the outer end of the lever 86 by operation of the treadle withdraws the rod 76 from engagement with the wedge member 80, allowing the clutch 125 projections to engage, and, when the treadle is released, the spring 78 raises the rod into the path of the wedge member 80 which is 130

thus caused to move axially of the shaft and to separate the clutch projections and stop the eccentric. This clutch is of the repeating type, so that by holding the treadle depressed repeated rapid impulses are imparted to the shoe support.

The kind of work upon which the illustrated machine is intended to operate is shown in Fig. 3, which represents a portion of a stitchdown shoe in which the welt has been carried around the periphery of the shoe and the ends lapped one over the other.

In the operation of the machine the bottom of the shoe is placed on the support 36 with the lap of the welt beneath the surface 20 of the tool 18 which enters the angle between the side of the shoe and the welt. The inclined position of the welt engaging face 20 and the cooperating surface of the support 36 enable the shoe to be presented to the machine at such an angle that the operator can observe the operation on the welt lap and locate it properly with respect to the tool. The abutment 22, by engagement with the edge 25 face of the welt, prevents the tool from entering the angle far enough forcibly to engage the shoe upper, thus preventing marring of the upper or catching of the tool on a projecting edge of the upper at a seam. The 30 abutment also prevents the pressure applied to the welt from broadening the welt laterally. The shoe having been properly located with respect to the tool, the operator depressed the treadle to pull downwardly on the 35 rod 92, thus causing the lever 86 to depress the rod 76 against the spring 78 and withdraw the upper end of the rod from engagement with the wedge member 80. Connection is thus established between the eccentric shaft 40 58 and the continuously rotating pulley 74 and the eccentric is rotated. Rotation of the eccentric pulls on the rod 52 and turns the lever 46 on its fulcrum 48, thus moving the slide 40 and the work support 36 perpendicularly toward the cooperating face 20 of the 45 tool 18, pressing the portion of the shoe between them to reduce the thickness at the welt lap. If the edge of the shoe is too thick or the resistance to compression of the work sufficiently great, the fulcrum 48 moves the 50 plunger 60 against the tension of the spring 66, thus momentarily transferring the fulcrum of the lever 46 to its pivotal connection with the link 44. If required by the nature of the work, the operator holds his foot on the 55 treadle so that rapidly repeated impulses will be imparted to the work support, the repeated hammering action of which will act to reduce the thickness at the welt lap progressively. 60 If desired, the shoe may be so positioned that only a part of the welt lap will be beneath the tool 18, and between successive actions of the support the shoe may be moved lengthwise of the lap to introduce other parts of the 65 lap beneath the tool so that the lap will be

reduced progressively of its length. The effect produced by the operation of the machine is illustrated in Fig. 4.

In operating upon some classes of work it is of advantage to have the tool 18 heated. For 70 such work the electric heating unit 32 is provided in the sleeve 16, the tool being thus heated by conduction from the heating unit. When heat is used, the operation of the machine will be substantially as described, the 75 heated tool acting more effectively to set the reduced welt lap and shoe edge in the condition produced by the applied pressure.

Having thus described my invention, what I claim as new and desire to secure by Letters 80 Patent of the United States is:

1. In a machine for pressing the welt lap of a stitchdown shoe in which the welt is carried entirely around the shoe and the ends lapped one upon the other, the combination 85 of a tool having a flat lower surface to engage the welt and having a lateral extent sufficient to cover the lapped area of the welt, a sole engaging member having a surface parallel to the welt engaging face of the tool, said surfaces being inclined downwardly and outwardly with respect to the machine, and power operated means including a powerful spring for relatively moving the tool and said sole engaging member in a direction perpendicular to their work engaging surfaces to apply predetermined powerful pressure to the material between them and to cause the lapped portions of the welt to be reduced in thickness.

2. In a machine for reducing the thickness of welt laps, the combination of a welt engaging tool, a cooperating work support between which and the tool the work is to be pressed, and mechanism comprising a lever having its forward end connected to effect relative actuation of the tool and support, a yielding fulcrum for the opposite end of the lever, and an eccentric connected to the lever at an intermediate point.

3. In a machine for pressing welt laps, the combination of a welt engaging tool, a cooperating work support movable relatively to the tool, a lever connected at one end to the work support, a yielding fulcrum supporting the opposite end of the lever, and means acting at an intermediate point of the lever to force the support toward the tool.

4. In a machine for pressing welt laps, the combination of a welt engaging tool, a cooperating work support movable relatively to the tool, a lever connected at one end to the work support, a yielding fulcrum supporting the opposite end of the lever, a power driven eccentric, and an eccentric rod connected to the lever between its ends.

5. In a machine for pressing welt laps, the combination of a welt engaging tool, a slide mounted for movement toward and from said tool, a sole support on the slide, a lever con-

- 5 nected to the slide, an eccentric connected to the lever between its ends to operate the work support, and a yielding member on which the lever is fulcrumed to limit the pressure on the work produced by operation of the eccentric.
- 6 6. In a machine for pressing welt laps, the combination of a welt engaging tool, a slide mounted for movement toward and from said tool, a sole support on the slide, a plunger arranged for movement parallel to the slide, a spring arranged to resist movement of the plunger in one direction, a lever connecting the slide and plunger, and an eccentric connected to the lever between its ends to operate the shoe support, said spring functioning to limit the force applied to the shoe support.
- 7 7. In a machine for pressing welt laps, the combination of a welt engaging tool, a slide mounted for movement toward and from said tool, a shoe support on the slide, a plunger arranged for movement parallel to the slide, a stop for the plunger, a spring arranged to hold the plunger against the stop, means for varying the tension of the spring, a lever connected to the slide, and power-operated means connected to the lever for operating the slide, the pressure imparted to the slide by the operation of the power means being limited by the tension of said spring.
- 8 8. In a welt lap pressing machine, a welt engaging tool having a downwardly and outwardly inclined face for engaging the welt lap, a member having a face substantially parallel to the welt engaging face of the tool and cooperating therewith to press the work, a slide arranged for movement perpendicularly to the operating face of the tool and carrying the member, means for adjusting said member relatively to the slide to vary the normal opening between the member and the tool, a lever connected to said slide, a yielding fulcrum for the lever, and power means having a constant stroke for operating the lever to effect movement of the slide toward the tool.
- 9 9. A machine for pressing the lapped ends of the welt of a stitchdown shoe having, in combination, a tool to engage the welt joint and having sufficient lateral extent to cover lapped portions of the welt, an abutment located to contact with the edge face of the welt and hold it from movement outwardly of the shoe, a sole support for engaging the portion of the sole opposite the welt lap, and power-operated means for relatively moving the tool and sole support to apply powerful pressure to the welt lap to cause its thickness to be reduced to the thickness of the remainder of the welt.
- 10 10. A machine for treating the lapped ends of the welt of a stitchdown shoe to reduce their thickness having, in combination, a tool to engage the welt and having sufficient lateral extent to cover the lapped portions of the welt, a support for engaging the portion of

the sole opposite the welt lap, power-operated means for effecting relative movement of the tool and the support perpendicularly of the welt, and a repeating clutch for controlling the power-operated means to enable rapidly repeated relative movements to be imparted to the tool and support to flatten the welt lap.

11. A machine for treating the lapped ends of the welt of a stitchdown shoe to reduce their thickness having, in combination, a tool to engage the welt lap, a support to engage the sole opposite the welt lap, said support being movable perpendicularly to the welt engaging face of the tool, power operated means for moving the support, and a repeating clutch for controlling the power means so that a succession of rapidly repeated hammer blows may be imparted to the support progressively to reduce the thickness of the welt lap to the thickness of the remainder of the welt.

12. In a machine for reducing the thickness of the lapped ends of the welt of a stitchdown shoe, the combination of a tool adapted to enter the angle between the side of the shoe and the welt, said tool having a sleeve conductively connected thereto, a heating unit in said sleeve, a support for the bottom of the shoe opposite to the tool, and means for relatively moving the tool and support perpendicularly to the welt engaging face of the tool to cause the welt lap to be pressed by the heated tool.

In testimony whereof I have signed my name to this specification.

ANDREW EPPLER.
